UNITED STATES PATENT OFFICE.

FRANK CRAFT, OF CLINTON, INDIANA, ASSIGNOR TO D. J. CRAFT, OF SCOTTLAND,
ILLINOIS.

ROTARY ENGINE.

1,273,743.

Specification of Letters Patent. Patented July 23, 1918.

Application filed November 17, 1917. Serial No. 202,597.

To all whom it may concern:

Be it known that I, FRANK CRAFT, a citizen of the United States, residing at Clinton, in the county of Vermilion and State 5 of Indiana, have invented new and useful Improvements in Rotary Engines, of which the following is a specification.

This invention relates to rotary engines and will be described with reference to the 10 adaption thereof as a steam engine although it will be apparent as the description proceeds that any agent under pressure such as air, gas or steam may be used for the purpose of operating the engine. The engine 15 is also adapted for use as an air compressor.

One of the chief objects of the invention is to produce in connection with a novel form of steam box or casing, a rotor carrying a plurality of oscillatory abutments of 20 novel construction and arrangement whereby maximum efficiency is obtained and leakage prevented.

Another object of the invention is to provide large and commodious inlet and exhaust ports which will insure free exhaust and a maximum power efficiency.

A further object of the invention is to provide a combined inlet and exhaust and reversing valve, controlled by a single operating lever, the valve being so arranged that it may be positioned to cut off the admission of steam and at the same time eliminate the danger of high compression and release any water that may have been 35 admitted from the boiler.

With the above and other objects in view, the invention consists in the novel construction, combination and arrangement of parts, herein fully described, illustrated 40 and claimed.

In the accompanying drawings:

Figure 1 is a vertical central section through an engine embodying the present invention.

Fig. 2 is a vertical longitudinal section taken on a line parallel to and at one side of the line on which Fig. 1 is taken.

Fig. 3 is a view looking toward the outer periphery of the rotor.

Fig. 4 is a vertical section on the line 4—4 of Fig. 1 showing one of the elongated inlet and exhaust ports.

Fig. 5 is a central vertical section on the line 5—5 of Fig. 1.

Fig. 6 is a detail perspective view of one of the oscillatory abutments.

In the embodiment of my invention, illustrated in the accompanying drawings, 1 designates a box-like casing inclosing a steam chamber 2 and having supporting extensions 3 to provide for mounting the engine on a base (not shown).

Within the casing 2, there is a substantially cylindrical wall 4 contained within the steam chamber 2 and formed at diametrically opposite sides with circumferentially elongated ports 5 and 6. The wall 4 is preferably formed or cast integrally with the casing 1. Extending through the oppositely located heads 7 of the rotor chamber 70 is the engine shaft 9 which is eccentric to the inner surface of the wall 4. Fast on the shaft 9 is a rotor 10 of cylindrical formation, the arrangement described, leaving a crescent shaped expansion chamber 11 between the periphery of the rotor and the bottom portion of the cylindrical wall 4 hereinabove referred to.

The rotor 10 is formed with a plurality of arcuate guide ways 12 and recesses 13 intersecting the guide ways 12, said recesses 13 being designed to receive and admit of the inward and outward movements of the arms 14 of a series of oscillatory abutments 16 each of which is of arcuate formation 85 and adapted to move into and out of the respective guide way 12. The arm 14 extends centrally from the abutment 15 and the recess 13 is correspondingly arranged centrally of the periphery of the rotor. Therefore the relatively wide abutment 15 projects from opposite sides of the arm 14 as clearly shown in the drawings. The outer edge of each arm 14 and abutment 15 is described on the arc of a circle of which the 95 axis of the shaft 9 is the center and when each abutment is at the inner limit of its movement, the said outer edges lie flush with the periphery of the rotor. Each abutment 15 is connected by a pivot 16 to the 100 rotor.

A valve chest 17 is mounted upon the steam box or casing 1 and embodies an inlet 18 and an outlet or exhaust 19. The inlet 18 communicates with the top or side wall of the valve chest and the exhaust 19 is located at one end of the valve chest which is preferably of cylindrical formation. Mounted adjustably in the valve chest 17 is a slide valve 20 of piston-like formation having at 110 the opposite ends thereof cylindrical valve faces 21 and 22 and provided between said

valve faces with an annular inlet port 23. The valve is of open center formation to provide an exhaust port 24 which extends entirely through the valve from end to end. 5 The valve is fixedly connected to a stem 25 which works in a head 27 at one end of the valve chamber 17. The valve stem 25 is connected at its outer end by means of a link 28 to a thumb latch lever 29 connected pivotally at 30 to a support 31 shown as secured to the casing 1, 32 representing a rack with which the latch 33 of the lever 29 engages. The rack 32 is formed with three notches 34 so that the lever 29 may be set in any one 15 of three positions, the central position representing the position of the valve 30 when the steam is cut off, and the other two positions representing the positions of the valve for driving the engine in opposite directions. 20 The central position of the valve 20 is such that no steam is admitted to the engine but the exhaust ports are slightly open thereby eliminating danger of high compression and also releasing any water that may collect 25 or be pulled over from the boiler. The valve chest 17 communicates with the steam chamber 2 by means of two combined inlet and exhaust ports 35 and 36. In the inner wall of the valve chest there are formed annular 30 steam grooves or passages 37, 38 and 39. The position of the valve for running the engine in one direction is clearly shown in Fig. 1. The steam enters at 18, passes along the groove 38 through the port 23 and the port 36 into the steam chamber 2. It then acts 35 on the rotor abutments, driving the rotor in the direction indicated by the arrow in Fig. 1. The steam then passes out through the port 6 which then acts as an exhaust port, 40 and on through the port 35 and out of the final exhaust port 19. When the valve 20 is shifted to the other limit of its movement, the movement of the steam is in the reverse direction with regard to the rotor and casing 45 and after passing out through the port 32, the steam passes through the exhaust port 24 of the valve and outwardly through the final exhaust 19. When the valve 20 is in its intermediate position, it cuts off the 50 admission of steam and leaves the exhaust ports 35 and 36 slightly open for the purpose above stated.

Each of the abutments 15 will be provided in the opposite side edges thereof with packing strips 40 and will also be provided in the outer edge thereof with another packing strip 41 and in the face thereof with one or more packing strips 42. The packing strips just referred to are of course intended 55 to reduce to a minimum the liability of leakage of steam between the contacting faces of the abutments and the rotor and casing.

I claim:—

1. In a rotary engine, the combination of a casing inclosing a chamber adapted to receive an expansive agent, a cylindrical wall within said casing formed with diametrically opposite circumferentially elongated ports, a shaft having an eccentric mounting within said cylindrical wall, a rotor fast on said shaft with its periphery eccentric to the inside of said cylindrical wall, said rotor being formed with arcuate guide ways and recesses intersecting the same, a plurality of abutments of arcuate formation movable into and out of said guide ways, arms extending from said abutments and pivotally mounted in said recesses, and a valve controlling the admission to and exhaust from the chamber between said cylindrical wall and outer casing. 65 70 75 80

2. In a rotary engine, the combination of a casing inclosing a chamber adapted to receive an expansive agent, a cylindrical wall within said casing formed with diametrically opposite circumferentially elongated ports, a shaft having an eccentric mounting within said cylindrical wall, a rotor fast on said shaft with its periphery eccentric to the inside of said cylindrical wall, said rotor being formed with arcuate guide ways and recesses intersecting the same, a plurality of abutments of arcuate formation movable into and out of said guide ways, arms extending from said abutments and pivotally mounted in said recesses, and a valve controlling the admission to and exhaust from the chamber between said cylindrical wall and outer casing, said valve having an axial exhaust port extending therethrough, adapting the valve to control both the intake and exhaust. 85 90 95 100

3. In a rotary engine, the combination of a casing inclosing a chamber adapted to receive an expansive agent, a cylindrical wall within said casing formed with diametrically opposite circumferentially elongated ports, a shaft having an eccentric mounting within said cylindrical wall, a rotor fast on said shaft with its periphery eccentric to the inside of said cylindrical wall, said rotor being formed with arcuate guide ways and recesses intersecting the same, a plurality of abutments of arcuate formation movable into and out of said guide ways, arms extending from said abutments and pivotally mounted in said recesses, and a valve controlling the admission to and exhaust from the chamber between said cylindrical wall and outer casing, each of said abutments having packing strips in the side and outer edges thereof and in the convex face thereof. 105 110 115 120

In testimony whereof I affix my signature.

FRANK CRAFT.
